Application August 14, 1935, Serial No. 36,196

13 Claims. (Cl. 209—179)

This invention relates to improvements in process for an apparatus for the separation of solids in liquid suspension, and more particularly to process for, and apparatus for, the recovery of gold and similar noble metals from aqueous suspension or pulp of the finely divided ore. Previously, there have been many attempts to increase the effectiveness of mercury amalgamation process by the use of a direct current passed 5 through the metalliferous suspension, the mercury amalgamated surface being the cathode or negative pulp of the circuit. It has long been known that the chief difficulty in amalgamation processes of this type has been to keep the mercury pure, to prevent the mercury from flouring or dividing up into small globules, and to keep the mercury interface with the pulp clean. It is common knowledge in the art that by the passage 10 of a direct electric current, either with or without sodium or some other chemicals, the surface of the mercury for amalgamation is improved.

While a direct current passed through the mercury promotes amalgamation by releasing 25 nascent hydrogen, which cleanses the mercury-pulp interface, the entry, exit, and passage of the current through the mercury actually creates oxidation and flouring of the mercury. The favorable cleansing action of the released nascent 30 hydrogen and the favorable lessening of the interfaced surface tension by the agitation of the interface, are often more than offset by the loss of mercury available for amalgamation.

The electrode which serves to conduct the 35 direct current into the mercury, unless it is of a material which will not react with mercury, forms undesirable mercury alloys and combinations. The passage of the current from the negative electrode into the mercury causes the formation 40 of dark mercury oxides, which mercury oxides generally collect on the surface of the mercury and work their way toward the positive electrode. Such effects render a portion of the mercury surface unavailable for amalgamation purposes. 45 After a run of several hours, moreover, it will be found that a substantial percentage of the mercury has been rendered inactive for amalgamation purposes through the formation of the mercury alloys and mercury oxides. These conditions have rendered such devices either inoperable or very inefficient for long runs.

It has been discovered that by insulating the 50 mercury carrying plate or holder from the trough or groove carrying the pulp, and by passing the

electrical current into the pulp by terminals ending therein and not coming into contact with the mercury itself or with the amalgamation plate, the current will pass along the interface with the favorable results desired, and without the deleterious effects discussed in the previous paragraph. While a portion of the current passes directly through the pulp, a portion enters the mercury interface and flows along it, creating the desired nascent hydrogen and modifying the 10 surface tensions at the interface so as to sharply increase the speed and extent of amalgamation. Apparently a portion of the hydrogen enters the surface of the mercury, creating a spongy 15 condition at the interface which modifies the surface tension, cleans the mercury, and prevents 20 fouling, oxidizing and flouring conditions of the mercury.

Amalgamation takes place at the point of contact of the mercury with the pulp which contains 25 the gold in liquid suspension, which point of contact is termed the interface. The water or pulp has a surface tension at this point, as has also the mercury. The gold particles must be passed through these surface tensions at the interface 30 and into the mercury itself in order to effect amalgamation. The passage of the current across the surface of the mercury, with its attendant release of nascent hydrogen, creates a spongy 35 surface on the mercury, as mentioned above, with lessened surface tension and thus increased amalgamation. It has also been found that vibration of the mercury-pulp interface, with its attendant wave motions, reduces the effective 40 surface tension and also increases the rate of amalgamation. In the particular devices disclosed herein, it has been found that this interface pulsation can be favorably increased through the use of a pulsating direct current.

It is an object of this invention to provide simple and effective means for increasing the recovery of finely divided gold in mercury amalgamation extraction processes; and it is a further object of this invention to provide means for increasing the effectiveness of the well known extraction processes, in such form as to be capable of addition to existing equipment without necessitating costly alterations or replacements. Other 45 features and advantages of this invention will be apparent from the following description and the drawings, in which—

Fig. 1 is a perspective view of the amalgamating trough embodying this invention; Fig. 2 is a 50 55

sectional view along the lines 2—2 of Fig. 1; Fig. 3 is a vertical sectional view of centrifugal apparatus embodying this invention; Fig. 4 is a detailed fragmentary sectional view of the wall of the bowl; Fig. 5 is a schematic view of the wiring; Fig. 6 is a plan view of a trough illustrating a different embodiment of this invention; Fig. 7 is a bottom plan view of one of the transverse members in Fig. 6; and Fig. 8 is a fragmentary sectional view along the line 8 of Fig. 6.

Referring more particularly to Figs. 1 and 2, an amalgamating trough 10 is shown formed of metal or other solid material. This trough is lined with an insulating material 11, such as hard or soft rubber. On the inner surface of the rubber rests an amalgamating plate 12, which plate is preferably of silver or of a silver-plated metal. On this amalgamating plate is a coating of mercury 13, which mercury substantially covers the entire bottom of the trough. In the walls of rubber, above the surface of the mercury but at a level adapted to contact a gold bearing pulp flowing through the trough, are placed metal contact strips or electrodes 14 and 15. These electrodes are relatively narrow strips, spaced a distance approximately equal to their length, and connected by the lead wires 16 and 17 to the supply wires 18 and 19. A suitable inlet or supply means 20 is provided, and an outlet trough 21 serves as an exit for the pulp. The trough may also, if desired, be provided with riffles 22.

In operation, the trough is supplied through the inlet means 20 with a continuous flow of pulp, comprising a multifarious liquid suspension. This pulp spreads out, covers the entire lower surface of the trough to a depth substantially equal to the upper edges of the rows of electrodes 14 and 15, and passes through the trough and out the exit means 21. The force of gravity tends to cause the gold particles to drop to the bottom of the pulp, into contact with the mercury-pulp interface. The supply wires 18 and 19 are fed with direct current, or with pulsating direct current, from any common source not here shown since such source forms no part of the present invention. The flow of current transversely of the trough through the pulp, the interface, and the mercury considerably increases the speed of amalgamation, prevents the mercury from flouring, cleanses the mercury by a release of nascent hydrogen, avoids polarization and does not cause oxidizing or other undesirable effects in the mercury.

Upon the completion of a run, after substantially all of the mercury has been amalgamated with gold, the amalgamating plate 12 is removed and the mercury gold amalgam thereon is treated for the recovery of the gold in any of the well known manners, as by filtration through chamois, followed by distillation of the thus separated concentrated amalgam, and acid treatment of the resulting metallic residue. The trough and plate may be then cleaned, the substantially pure mercury returned, and the trough is again ready for another run.

As disclosed above, the current supplied to the electrodes through the wires 18 and 19 is preferably a pulsating direct current. Such a current may be supplied by a mercury arc rectifier of the common commercial type, for example, or by superimposing an alternating current upon a direct current of a voltage at least equal to the peak voltage of the alternating current. As a theoretical explanation of the increased efficiency of the pulsating direct current as compared to the

use of a pure direct current, it is believed that the periodic variations in surface tension at the mercury-pulp interface resulting from the changes in voltage tend to produce a surging to and fro of the interface, whereby amalgamation is promoted. These variations in surface tension are also believed to be effective in setting up wave motions and wave patterns in the interface, whereby the entrance of a gold particle into the mercury is promoted, as long as such wave motions are not of such force as to produce cavitation. It is to be understood, however, that whatever other explanation or theory might be developed to explain the action, it has been found that the arrangement herein described is actually of practical value in accelerating the amalgamation process, and that the invention is not concerned with the theory of operation just presented.

Referring more particularly to Figs. 3, 4, and 5, the invention is shown embodied in amalgamating apparatus of the centrifugal type.

In the particular embodiment of the invention illustrated in these figures the reference numeral 23 indicates a metal bowl or shell, which bowl is fastened to a rotatable member 24, as by the bolts 25. The rotatable member 24 is supported by a shaft 26 riding on the thrust bearings 27, which bearings are journaled in a member 28 supported by the transverse member 29, which member is in turn supported by the frame 30. The shaft 26 may be provided with a fly wheel 31 to eliminate variations in the speed of rotation, and may be driven by any convenient means, as by the belt 32 on the pulley 33, which belt is in turn driven by a source of power not here illustrated. The rotatable member 24 is journaled in the bearings 34, which bearings contact a second transverse member 35, which member is also supported by the frame 30.

The bowl 23 is here shown as having therein an inner bowl 36 of hard rubber, and an inner layer 37 of soft rubber, which layer is here shown as passing over the top of the hard rubber 36 and bowl 23 to form a flange 38. The soft rubber lining or bowl portion 27 has therein a continuous spiral groove 39. This groove is here disclosed in the preferred spiral form, although a series of concentric spaced annular grooves may be used. In the bottom of the groove the amalgamating plate or strip 40 is fastened by any convenient means, as for example by small cleats clinching into the soft rubber 37. Adjacent the edges of the grooves are mounted electrodes 41 and 42. These electrodes do not contact the amalgamating strip 40, nor is there any direct electrical connection between them.

An inlet pipe or supply means 43 extends into the bowl substantially axially thereof, and is non-rotatably supported by the transverse member 44 mounted on the frame 30. An open spider or set of supporting arms 45 are rotatably journaled on the inlet pipe 43, as by the bearings 46, and contact the upper edge of the bowl, or of the lining 37, as at the point 47. This spider serves to steady the bowl, and to prevent vibration at high speeds of rotation. A dome or cupola member 48 covers the bowl, and an outlet is provided for pulp flowing over the edge of the bowl by the sloping bottom 49 of the container 50, which container has an outlet opening 51 therethrough. The outlet may, if desired, be provided with a series of riffles 52 to trap any mercury which may have escaped over the top of the bowl. The strips or electrodes 41 and 42 are connected, respectively, to supply wires 53 and 54, as will be more

readily apparent from a consideration of Fig. 5. It will be noted that each row of electrodes 42 are serially connected, the rows being connected in parallel to the supply wire 54. Similarly each series of electrodes 41 is connected to the supply wire 53. The wires 53 and 54, referring back to Fig. 3, terminate in tips or jacks 55 and 56, mounted in the hard rubber extension piece 57, and adapted to be received by the sockets 58 and 59, which sockets are mounted in the rotatable member 54. The lead wires 60 and 61 extend to the brushes 62 and 63, which brushes are adapted to contact the slip rings 64 and 65, non-rotatably mounted on a portion 66 of the transverse member 35. The rings 64 and 65 have connected thereto supply wires 67 and 68, through which current of any desired type may be supplied to the apparatus by means not shown here.

Referring more particularly to the fragmentary sectional view of Fig. 4, it will be noted that the grooves 39 overhang, that is, they are wider at the bottom than at the top. This serves to enable a broader amalgamated surface, and to help prevent the mercury from climbing over the edge of the groove. It will be noted that the electrodes, as 41 and 42, are mounted in the soft rubber immediately adjacent the edge of the groove, so that current flowing therebetween will be across the groove and partly through the mercury pulp interface. The lead wires 53 and 54 are preferably mounted in grooves, as 69, in the hard rubber 36. It is to be understood that the upper supporting member 44 and the inlet pipe 43 may be slid upward on the frame 30, or completely removed therefrom, whereupon the hard rubber bowl 36 and the soft rubber lining 37 may be lifted out of the metal bowl 23, the electrical connections separating where the jacks contact the sockets. A new lining piece may then be dropped into the bowl, and the process of amalgamation continued while the mercury amalgam is being removed from the surface of the amalgamating plate 40.

When the apparatus is in the condition illustrated in Fig. 3, a quantity of mercury sufficient to cover the bottom of the grooves 39 and the amalgamating plate 40 therein is first poured into the supply pipe 43, and the bowl is rotated to force the mercury up into the grooves. As soon as the mercury has substantially filled the entire groove, and has reached the uppermost level of the spiral, the flow of pulp is started into the bowl, the centrifugal force causes the pulp supplied to the lower central portion of the bowl to flow up the sides and over the flange 38, whereupon it flows along the bottom 49 and out the opening 51. During its passage up the wall of the bowl, however, the pulp has come into contact with the mercury and has been acted upon by the electric current, either pulsating or direct, and the combination of these factors with the centrifugal separation has caused substantially all of the gold particles in liquid suspension in the pulp to be amalgamated with the mercury. The direction of rotation of the bowl is preferably opposed to the direction of the spiral groove, so that the tendency of the centrifugal force to throw the mercury out of the top of the bowl is substantially neutralized. In order to keep the preferred depth of pulp flowing up the side of the bowl, any common automatic means may be used for regulating the speed of rotation of the bowl.

While the pulp is forced upward and outward over the edge of the bowl, the slope of the bowl

is such for the speed of rotation used, for example 300 R. P. M., that gravity, the overhanging edges of the grooves, and the reverse trend of the spiral keep the mercury in the amalgamating grooves and do not throw it out of the top of the bowl. The fact that the amalgamating plate is a continuous spiral, and that the electrodes are all interconnected serially by copper wires, also aids in maintaining uniform potential at every point of the amalgamating surface.

The effective action at the interface, and more particularly the cleansing action of the nascent hydrogen, is apparently increased in proportion to the extent that polarization is prevented. This is practically eliminated by such disposition of the terminals that they overlap eccentrically and are separated by insulation, but pass the pulsating direct current through the pulp to the interface of the mercury. This alternative arrangement of the terminals requires that they be carried by an additional member in close enough proximity to the amalgamating plate carrying the mercury to penetrate the pulp stream and pass the current to the interface.

In a particular embodiment of this invention illustrated in Figs. 6, 7, and 8, the method of passing the current to the interface from spirally arranged electrodes is illustrated although any method of disposing the terminals of the electrodes to pass the current through the mercury-pulp interface has been found to accelerate the amalgamating action. With ores where sulfides are troublesome, this form of application is found to be most effective. The reference numeral 75 indicates an amalgamating trough similar to that disclosed and described in connection with Figs. 1 and 2. This trough has an inlet 76 and an outlet 77, and is adapted to have pulp, or an aqueous suspension of fine gold particles pass therethrough. The trough 75 has located therein and slightly raised above the level of the amalgamation plate 78, ledges or shoulders 79. These shoulders support transverse members 80, which transverse members are preferably formed of some insulating material resistive to the abrasive effect of the pulp. These transverse members 80 are spaced, and so arranged that a portion of the pulp flow passes beneath them and a portion above them, thus serving to create counter-currents and cross-flow which insure all of the pulp passing beneath the amalgamation plate 78 and the lower surface of at least one of the transverse members 80.

The under-surface of the transverse members 80 is composed of two different levels, one of these levels having mounted therein the spiral electrode 81, and the other level having partially mounted therein the spiral electrode 82. The portion of the electrode 82 which is not mounted in the transverse member 80 itself, is supported therefrom by the small insulating blocks 83. These blocks insure good mechanical support of the electrode 82, without preventing the desired electrical action on the pulp passing between the transverse member 80 and the amalgamation plate 78. In this particular embodiment of the invention the electrode closest to the amalgamation plate, here disclosed as the electrode 82, is preferably the negative electrode for the application of the pulsating direct current. The negative electrodes in each of the transverse members are preferably connected in parallel to some supply line and current source, not here disclosed, and the positive electrodes are similarly connected.

The nascent hydrogen released by the passage of current through the pulp seems to spread in a desirable manner from the electrodes of this type, and to effectively cleanse the mercury interface through its action. Since the electrodes overlap, cross-currents of nascent hydrogen are apparently sent up, and little or no polarization of the mercury-pulp interface occurs.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as possible in view of the prior art.

What we claim as new, and desire to secure by Letters Patent, is:

1. An amalgamation device of the character described, including: a container; an amalgamation plate in said container; a layer of mercury on said plate; a pair of electrodes in the walls of said container above the level of, and not in contact with the mercury, the sum of the distances from each electrode to the mercury being less than the interelectrode distance; means for passing a pulp comprising a liquid suspension of particles of noble metal over said mercury; and means for passing current through the mercury-pulp interface, said circuit passing current from one of said pair of electrodes to the other thereof.

2. A device of the character described for recovering particles of noble metal from a pulp comprising a liquid suspension of finely divided ore, including: a container adapted to be rotated, said container having a groove in the wall thereof; an amalgamation plate in said groove; means for maintaining a layer of mercury on said plate in said groove; a pair of electrodes in the walls of said container on opposite sides of said groove, said electrodes being above the level of said mercury; means for passing said pulp over said mercury; and means for passing an electric current through the mercury-pulp interface, said means including said electrodes.

3. A device of the character described for recovering particles of noble metal from a pulp comprising a liquid suspension of finely divided ore, including: a container of substantially parabolic cross-sectional shape, said container being adapted to be rotated; a groove in the wall of said container; an amalgamation plate in the bottom of said groove; means for maintaining a layer of mercury on said plate, said means including rotation of said container; a pair of electrodes in the walls of said container adjacent opposite edges of said groove, said electrodes being above the level maintained by said mercury; means for passing said pulp over said mercury; and means for passing an electric current through the mercury-pulp interface, said means including said electrodes.

4. Apparatus of the character claimed in claim 3, wherein said current is a pulsating direct current.

5. A device of the character described for recovering particles of noble metal from a pulp comprising a liquid suspension of finely divided ore, including: a container of substantially parabolic cross-sectional shape having a spiral groove in the wall thereof, said container being adapted to be rotated in a direction opposed to said spiral; an amalgamation plate in the bottom of said

groove; means for maintaining a layer of mercury on said plate; electrodes in the walls of said container between the edges of adjacent turns of said spiral, said electrodes being adjacent the edges of said groove and above the level of the mercury therein; means for passing said pulp continuously over said mercury; and means for passing an electric current through the mercury-pulp interface, said means including the electrodes.

6. Apparatus of the character claimed in claim 5, wherein said current is a pulsating direct current.

7. A device of the character described for recovering particles of noble metal from a pulp comprising a liquid suspension of finely divided ore, including: a container of substantially parabolic cross-sectional shape, said container having a spiral groove in the wall thereof; means for rotating said container in a direction opposed to said spiral; an amalgamation plate in said groove; means for maintaining a layer of mercury on said plate; means for continuously passing pulp over said mercury, said means including an inlet substantially axially disposed in said container; electrodes in the walls of said container between the edges of adjacent turns of said groove, said electrodes being above the level of said mercury; and means for passing an electric current through the mercury-pulp interface, said means including said electrodes.

8. The method of extracting a metal from an ore pulp by amalgamation with mercury, in which the pulp is brought into contact with the mercury and simultaneously an electric current is passed through the pulp, the mercury and the mercury-pulp interface from a pair of electrodes above the level of, and not in contact with said mercury, the sum of distances from each electrode to the mercury being less than the inter-electrode distance.

9. The method of extracting a metal from a pulp comprising an aqueous suspension of particles of the metal in which the pulp is brought into contact with mercury and simultaneously an electric current is passed from an electrode into said pulp across said mercury-pulp interface, and out of said pulp through another electrode, neither of said electrodes being in contact with the said mercury and the sum of the distances from each electrode to the mercury being less than the inter-electrode distance.

10. The method of extracting a metal from a pulp comprising an aqueous suspension of fine particles thereof in which the pulp is brought into contact with mercury and simultaneously a pulsating direct current is caused to flow across the mercury-pulp interface from a pair of electrodes above the level of, and not in contact with, said mercury, the sum of the distances from each electrode to the mercury being less than the inter-electrode distance.

11. The method of extracting a metal from a pulp comprising an aqueous suspension of the metal, in which the pulp is brought into contact with mercury and simultaneously an electric current is passed through a pair of electrodes above the level of, and not in contact with, the said mercury, the sum of the distances from each electrode to the mercury being less than the inter-electrode distance, said pulp, mercury-pulp interface, and mercury in a direction substantially parallel to the plane of said mercury-pulp interface.

12. A device of the character described for re-

covering particles of noble metal from a pulp comprising a liquid suspension of finely divided ore, including: a container of substantially parabolic cross-sectional shape, said container being adapted to be rotated; a spiral groove in the wall of said container; an amalgamation plate in the bottom of said groove; means for maintaining a layer of mercury on said plate; said means including rotation of said container; a pair of electrodes in the walls of said container adjacent opposite edges of said groove, said electrodes being above the level maintained by said mercury; means for passing said pulp over said mercury; and means for passing an electric current through the mercury pulp interface, said means including said electrodes.

13. A device of the character described for recovering particles of noble metal from a pulp comprising a liquid suspension of finely divided ore, including: a container of substantially parabolic cross-sectional shape having a spiral 5 groove in the wall thereof, said container being adapted to be rotated in a direction opposed to said spiral; an amalgamation plate in the bottom of said groove; means for maintaining a layer of mercury on said plate; means for passing said 10 pulp continuously over said mercury; and means for passing an electric current through the mercury pulp interface, said means including electrodes.

CHARLES REVELL HOLDEN. 15
MIGUEL DROBINSKY.
